(57) CLAIM

The ornamental design for footwear, as shown and described.

DESCRIPTION

FIG. 1 is an isometric view of footwear.

FIG. 2 is a front elevation view of the footwear of FIG. 1.

FIG. 3 is a rear elevation view of the footwear of FIG. 1.

FIG. 4 is a right side elevation view of the footwear of FIG. 1.

FIG. 5 is a left side elevation view of the footwear of FIG. 1.
